UNITED STATES PATENT OFFICE

HARRIE F. TALBOT, OF PERU, ILLINOIS, ASSIGNOR TO RADIUM DIAL COMPANY, OF NEW YORK, N. Y., A CORPORATION OF DELAWARE

THERMAL CUT-OUT PLUG

Application filed November 22, 1929. Serial No. 409,030.

This invention relates to electric plugs, and more particularly to a cut-out plug of the circuit-breaker type in which the circuit will be automatically broken when the current reaches a certain amount without injury to any of the parts of the plug.

One object of the invention is to provide a circuit breaker plug of the above nature employing a bimetallic latch and spring catch which may be restored to operating position after the circuit has been broken by manually twisting the cap and without requiring replacement of any of the parts thereof.

A further object is to provide a device of the above nature which will be simple in construction, inexpensive to manufacture, easy to assemble and manipulate, and very efficient and durable in use.

With these and other objects in view, there has been illustrated on the accompanying drawings one form in which the invention may be conveniently embodied in practice.

Fig. 1 represents a vertical longitudinal sectional view of the cut-out plug.

Fig. 2 is a similar longitudinal sectional view of the same, the section being taken at right angles from the view of Fig. 1.

Fig. 3 is a transverse horizontal sectional view taken along the line 3-3 of Fig. 2 looking downwardly, and showing the bimetallic latch out of engagement with the top of the spring catch.

Fig. 4 is a transverse sectional view, similar to Fig. 3 showing the bimetallic latch in locking engagement with the top of the spring catch.

Referring now to the drawings in which like reference numerals denote corresponding parts throughout the several views, the numeral 10 indicates a circular body shell of insulating material, said body shell being provided with a downwardly extending slot 11 in one side thereof. The outer periphery of the body shell 10 is provided near its top with a rectangular groove 12, which is adapted to receive a resilient curved strip metal spring 13 surrounding substantially three quarters of the circumference of the base of the slot 12. The spring 13 has one end bent over at 14, said end 14 having an aperture 15

for receiving a set-screw 16 threaded into an aperture 17 formed in a cup-shaped cover member or cap 18, also of insulating material. By means of this construction, it will be seen that when the screw 16 has been driven to its innermost position, it will be impossible to remove the cover 18 from the body shell 10.

The lower half of the body shell is threaded to receive an outer metallic shell contact 19 which has an inturned bottom flange 20 adapted to seat in a groove 21 in an insulating base member 22 located below the body shell 10.

In order to form a base terminal for the cut-out plug, provision is made of a tubular member 23 having an enlarged lower section 24 for engagement with the center contact of an electric socket. The construction of this base terminal has been described and claimed in a previous patent application by the same inventor.

Within the interior of the body shell 10 provision is made of an angular supporting member 25 having a bottom horizontal arm 26 secured upon the base 22 by heading over the top of the tubular section 23. The upper vertical arm 26a of the angular supporting member 25 is attached as by a rivet 26b to a downturned portion 27 of a bimetallic expansion latch 28. The free end 29 of the latch 28 is downturned and pointed for engagement with a groove 30 formed in the top of a spring catch 31, the latter having its lower end reversely bent upwardly at 32, and said upwardly bent end 32 is held securely in position between the outer portion of the body shell 10 and the shell contact 19.

Operation

After the circuit has been broken by the upward flexing of the bimetallic thermostatic latch 28 which automatically releases the spring catch 31 and causes it to spring outwardly, the device may be restored to its original operating condition merely by twisting the cap 18 in clockwise direction after first allowing the bimetallic latch 28 to cool off and resume its normal horizontal position. When the cap 18 is twisted, the inclined end of the metal spring 13 will engage the upper

part of the spring catch 31 forcing it inwardly until it snaps into locking engagement with the down-turned portion 27 of the latch 28.

5 While there has been disclosed in this specification one form in which the invention may be embodied, it is to be understood that this form is shown for the purpose of illustration only, and that the invention is not to be 10 limited to the specific disclosure but may be modified and embodied in various other forms without departing from its spirit. In short, the invention includes all the modifications and embodiments coming within the 15 scope of the following claims.

Having thus fully described the invention, what is claimed as new, and for which it is desired to secure Letters Patent, is:

1. In a cut-out plug, an insulating base 20 member, a central contact terminal and a shell contact terminal secured to said base member, an angular supporting member on said base connected with said central terminal, a bimetallic latch secured to the top of 25 said supporting member and having a down-turned extremity, a spring catch having a groove at its upper end extending upwardly from said outer shell terminal, said latch normally engaging said catch to close the circuit, said latch being automatically raised 30 out of contact with said catch when the current through the cut-out exceeds a safe limit.

2. In a cut-out plug, an insulating base 35 member, a central contact terminal and a shell contact terminal secured to said base member, an angular supporting member on said base connected with said central terminal, a bimetallic latch secured to the top of 40 said supporting member and having a downturned extremity, a spring catch extending upwardly from said outer shell terminal, said latch normally engaging said catch to close the circuit, said latch being automatically raised out of contact with said 45 catch when the current through the fuse exceeds a safe limit, an outer insulating body shell, a cap on said body shell having a downwardly extending flange, and means in said flange to connect said latch and catch by manually rotating said cap after the circuit 50 has been broken.

3. In a cut-out plug, an insulating base 55 member, a central contact terminal and a shell contact terminal secured to said base member, an angular supporting member on said base connected with said central terminal, a bimetallic latch secured to the top of 60 said supporting member and having a down-turned extremity, a spring catch extending upwardly from said outer shell terminal, said latch normally engaging said catch to close the circuit, said latch being automatically raised out of contact with said catch when 65 the current through the fuse exceeds a safe limit, an outer insulating body shell, a cap

on said body shell having a downwardly extending flange, and means in said flange to connect said latch and catch by manually rotating said cap after the circuit has been broken. 70

4. In a cut-out plug, an insulating base member, a central contact terminal and a shell contact terminal secured to said base member, an angular supporting member on said base connected with said central terminal, a bimetallic latch secured to the top of 75 said supporting member and having a down-turned extremity, a spring catch extending upwardly from said outer shell terminal, said latch normally engaging said catch to close the circuit, said latch being automatically raised out of contact with said catch when the current through the fuse exceeds a safe limit, an outer insulating body shell, a cap on said body shell having a downwardly 80 extending flange, and a spring strip in said flange to connect said latch and catch by manually rotating said cap after the circuit has been broken. 85

5. In a cut-out plug, an insulating base member, a central contact terminal and a shell contact terminal secured to said base member, an angular supporting member on said base connected with said central terminal, a bimetallic latch secured to the top of 90 said supporting member and having a down-turned extremity, a spring catch extending upwardly from said outer shell terminal, said latch normally engaging said catch to close the circuit, said latch being automatically raised out of contact with said catch when the current through the fuse exceeds a safe limit, an outer insulating body shell, a cap on said body shell having a downwardly 95 extending flange, and a spring strip in said flange to connect said latch and catch by manually rotating said cap after the circuit has been broken. 100

In testimony whereof, I have affixed my 105 signature to this specification.

HARRIE F. TALBOT.
